[57] CLAIM

The ornamental design for a combined lavatory and
support pedestal, substantially as shown and described.

DESCRIPTION

FIG. 1 is a perspective view of a combined lavatory and
support pedestal illustrating my new design;
FIG. 2 is a front elevational view thereof;

FIG. 3 is a right side elevational view thereof, the left
side being a mirror image of the right side shown;

FIG. 4 is a top plan view thereof;

FIG. 5 is a rear elevational view thereof; and

FIG. 6 is a bottom plan view thereof.

FIG.1
